Company, Toledo, Ohio, a corporation of Ohio

Application October 30, 1937, Serial No. 172,025

9 Claims. (Cl. 91—55)

This invention relates to apparatus for coating containers, especially containers fabricated of paper and designed and intended for use in the packaging of perishable products, although in certain of its broader aspects it relates to the application of coatings to articles of various kinds and fabricated of different materials.

Paper containers of various kinds have heretofore been widely used in the packaging and distribution of many solid products, being attractive in appearance, light in weight, and comparatively inexpensive. The packaging of solid materials either in the form of single articles, or lump or granular substances, presents little difficulty and many machines for fabricating suitable containers intended for such use have heretofore been designed or suggested. The packaging of liquids, however, in paper containers, is much more difficult to successfully accomplish since by reason of the fibrous nature of the paper it readily absorbs liquids and, after the paper has become wet, it loses the greater part of its strength. Hence it is necessary, if a paper container for liquids is to be produced at a reasonable cost, to apply to its surfaces a coating layer of a substance impervious to liquid in order that the paper fibers of the container may not become wet and soft. Paper containers for the packaging and distribution of liquids must of necessity be of the self-supporting type and comparatively strong since the pressure of the liquid within the container is considerable even when the container is at rest, and the danger of failure is of course increased when the container is handled or transported. The material customarily chosen for the coating of paper containers in the usual case comprises paraffin or at least is a paraffin containing substance, it having been found that such coating material not only is liquid proof but has a certain stiffness when hardened, thus increasing the ability of the container to maintain its shape during handling and transportation, despite the internal pressure of the liquid. While coatings of various materials may be applied to paper containers in various ways it is preferable that the coating be applied by means of a dipping operation since by immersion in a bath of molten coating material it is assured that the coating is applied thoroughly to all areas of the container.

The present invention contemplates an apparatus for coating containers generally, but particularly containers which have been folded into tubular form and have one end (the bottom) closed and the other end open, and the apparatus

hereinafter to be described is intended to receive containers thus partially completed, effect the immersion thereof in a bath of the molten coating material, drainage in a heated atmosphere above the bath, introduction into the interior thereof of additional coating material, if necessary, and subsequent chilling of the coating material to effect its hardening. Coating of the containers in a nearly completed stage of fabrication is advantageous in that the container need be subjected to but few further operations which tend to disturb the coating already applied. Practically all containers fabricated of paper have certain portions of greater thickness than other portions. In the usual case the bottom of the container comprises two or more plies of paper and the side walls but a single ply or thickness. That portion of the container which is of greatest thickness has a tendency to absorb more coating material than those portions of less thickness and likewise is slower in cooling after its temperature has been raised by immersion in a molten bath of coating material. In accordance with the present invention these characteristics of the paper container are given full consideration and, after dipping and draining, the heavier bottom of the container is covered with an additional amount of coating material if excessive absorption of this material has occurred, likewise the cooling means is so designed and constructed that that portion of the container which tends to retain heat longest is subjected to the action of a cooling medium of higher heat conductivity than is that portion, or those portions, of the container which are of lighter section. For instance in the case of a tubular container with a multi-ply bottom the heavier bottom portion of the freshly coated container is immersed in a liquid bath cooled to a low temperature whereas the thinner portions of the container wall are sufficiently cooled and the coating material hardened by the simple application thereto of a current of cooled air or other gas. The cooling of the bottom of the freshly coated container, and of the side walls, are effected simultaneously so that the cooling of the entire container and the hardening of its coating layer is effected in a minimum of time, a consideration of much importance when the coating and cooling mechanisms comprise only portions of a complete automatic machine for the fabrication, coating, charging and sealing of paper containers.

Prior to cooling the container is automatically handled and manipulated by automatic mecha-

nism which is maintained in heated condition in order that it will not become clogged by hardening of the coating material thereon and a novel means for maintaining those various portions of the mechanism which come in contact with paraffin at any time has been devised. Likewise a novel means is provided for supplying the coating mechanism with freshly melted coating material to replace that carried away upon the surfaces of containers which have been immersed. The cooling system for effecting cooling of the volumes of air and liquid employed to cool the freshly coated containers is provided which system embodies a number of novel and important features. The invention likewise includes a number of additional elements, not above specifically mentioned, which contribute to the effectiveness of the mechanism as a whole.

By way of example, one embodiment of the coating apparatus is disclosed in the accompanying drawings, but it will be appreciated by those skilled in the art that the design and arrangement of numerous elements of the invention may be substantially modified without departure therefrom, particularly in adapting the same for the coating of containers of different shapes and sizes.

Figure 23 is an end view of the same;

Figure 24 is a perspective view of a container of the type which the apparatus has been particularly designed to receive and coat; and

Figure 25 is a section on line 25—25 of Figure 7.

The method of coating includes two principal steps, i. e., the step of actually applying the coating and the step of chilling and solidifying the coatings thus applied. In the apparatus for practicing the method the coating applying unit and the coating chilling unit, while in some respects independent of each other, are closely associated in order that a maximum efficiency of operation may be realized. The coating apparatus as a whole is, as a matter of fact, preferably designed to comprise an integral portion of a complete automatic machine for the formation of containers from scored paper blanks, coating of these containers, and the subsequent charging, closing and sealing of the same. Notwithstanding this the apparatus may well be employed independently of any container fabricating means and independently of the container charging, closing and sealing means, and may be used to coat containers which have been formed elsewhere, and which may also be charged, closed and sealed at a relatively remote point. The method of and apparatus for actually applying to a container a coating of paraffin or like substance will first be described.

In Figure 24 of the drawings a container of the type which the machine has been specifically designed to handle is illustrated in perspective and partially broken away. This container is fabricated of relatively thin stiff paper of good quality and comprises a body portion having four rectangular panels *a*, a foldable top portion *b* and a closure or bottom *c*, at its lower end, the container being coated with the selected material while in the stage of completion in which it is shown in Figure 24, the bottom *c* having been fully formed, but the top or upper end being open. It will be perceived that the body portion and top portion of the container are formed of a single thickness of paper but that the bottom is built up of several thicknesses, preferably three, and is of much heavier section than either the side wall or top. In the method of coating employed this difference in section between the bottom and other parts of the container is fully taken into account, as will hereinafter appear.

While various mechanisms for and methods of actually applying the molten coating material to the container walls may be employed, it is preferred that each container to be coated be actually dipped into a bath of molten coating material. All portions of the surfaces of the container walls and bottom may be brought into intimate contact with the coating material for any desired length of time and hence the effectiveness of the coating operation assured. It is preferred that a dipping unit such as illustrated in section in Figure 4 be employed. This mechanism comprises a closed chamber, generally designated at 10 the lower portion of which, indicated at 11, comprises a receptacle for a bath of molten coating material and the upper portion

of which comprises a housing for the means for passing containers through the bath in a definite manner and for retaining above the surface of the bath a volume of highly heated air. The specific means for receiving containers inserted into the chamber 10 at one point, moving such containers through the paraffin bath at the bottom of the chamber, and thereafter ejecting containers from the chamber, comprises no portion of the present invention and for a full and complete understanding of this mechanism reference may be had to the Henry T. Scott application, Serial No. 108,258, filed October 29, 1936. It need only be said here that containers are successively brought into predetermined position opposite an aperture in the chamber wall by mechanism which includes an oscillating container holding member 12, are thereafter thrust laterally through this aperture into successively presented container carriers 13, mounted upon an endless conveyor chain which is operated intermittently to lower the carriers 13 into the bath of coating material within the receptacle 11, the level of the upper surface of such coating material being indicated at 14, to transmit the containers through the bath in the direction of the arrow A and thence upwardly, as indicated by the arrow B, to a point generally indicated at C, at which point there is a discharge aperture in the chamber wall, and in position to be engaged by pusher fingers 16 mounted upon a sliding head 17, and successively thrust through the discharge aperture and into a container receiving member 18.

Each container is lowered into the bath of molten coating material bottom end foremost and removed from the bath bottom end foremost so that in its upward movement in the direction of the arrow B (Figure 4) the open end of the container is downwardly directed and excess coating material may escape from its inner wall surfaces as well as from its outer wall surfaces so that, by the time the container has reached the position indicated at C, it is quite ready for ejection from the chamber 10.

The pusher head 17 is slidably mounted upon guide rods 19 and immediately below the slide is a box-like member 20 which comprises a steam chest, steam at the desired temperature being conducted to this chest by means of a pipe 21 and exhaust steam and water of condensation passing therefrom through a pipe or conduit 22. By means of the steam chamber 20 all portions of the container ejecting mechanism just described may be maintained at temperatures above that at which the coating material liquifies and hence any coating material which may be deposited upon these members will not solidify but will drop downwardly into the bath below. The steam chamber 20 likewise functions to maintain the temperature of the atmosphere within the chamber 10 above that of liquification of the coating material so that the containers moving upwardly to the point of discharge after having been coated pass through this heated atmosphere and normal drainage of the coating material therefrom may occur. It will be understood that the operation of the coating unit is intermittent or step-by-step (although it may be continuous if desired), uncoated containers being successively introduced and, simultaneously with the introduction of each uncoated container, a fully coated container ejected therefrom.

The receptacle 11 for the molten coating material has a double bottom, the space 25 inter-

mediate the bottom plates comprising a steam chamber, conduits 26 being provided for introducing steam into the same from opposite sides and a conduit 27 conducting away exhaust steam and water of condensation. The temperature within the steam chamber is at all times maintained sufficiently high to keep the coating material in receptacle 11 in molten condition, automatic steam flow regulating means hereinafter 10 to be referred to being provided for regulating the steam flow.

Referring now to Figures 5 and 5a it will be perceived that the member 18 is in the nature of an elongated rectangular open-sided frame and this frame is mounted upon a rock shaft 30 by means of which it may be moved from the position in which it is shown in Figure 5 to the position in which it is shown in Figure 5a. When in the position in which it is shown in Figure 5 15 it may receive a container ejected from the chamber 10, being then in register with the discharge aperture of chamber 10, and when rocked downwardly to the position in which it is shown in Figure 5a such container, which is indicated at R, is vertically disposed with bottom lowermost. When so positioned also the freshly coated container lies in front of a vertically disposed portion 31¹ of a flat angular member 31 shown in Figures 6 and 7, the lower horizontally disposed portion 31² of which is secured to the end of a reciprocating member 32 which, when drawn to the left (Figures 6 and 7), will withdraw the container R from the container handling member 18 and move it on to a conveyor 35 by means of which it may be advanced toward the left (Figure 6). A plurality of containers are shown in chain lines in Figure 6. During the time, however, that each container is maintained within the rocking member 18 its temperature is 40 maintained sufficiently elevated so that chilling of the coating material cannot occur, member 18 being itself maintained in a closed chamber the walls of which are steam heated.

The rear wall 33 of this chamber comprises 45 also an exterior wall of the chamber 10, which wall is at all times maintained in heated condition by the heating means within chamber 10. Side wall 34, top 35 and arcuate side wall 36 of the chamber in which member 18 is housed are 50 hollow and together comprise one continuous chamber for a heating medium. Steam is introduced into such chamber through a conduit 37 entering the same at its highest point, lower conduits 38 and 39 being adapted to transmit 55 away excess steam and water of condensation. The front wall 40 of the chamber within which the container handling member 18 is located need not be heated. At all times, therefore, subsequent to the introduction of the container into the chamber 10, and prior to the operation of the member 31 to effect removal of the container 60 from the chamber which houses member 18, the container is either maintained in a bath of molten coating material or in a highly heated atmosphere 65 which prevents chilling and solidification of such material after its application.

When a container reaches the position in which it is shown in Figure 6, immediately in front of pusher member 31, the coating material upon its vertically disposed walls will tend to drain downwardly, the material flowing down its inner walls being collected on the bottom of the container and that upon the outer walls dripping downwardly and returning to the paraffin receptacle 11, over which it is still positioned, as may

be seen from an inspection of Figures 3, 6 and 7. At this point, and while the container is still highly heated and the coating material thereon in fluid condition, it may be desired to introduce a supplemental quantity of coating material into the interior thereof, to be distributed over the container bottom. This is especially true where the container is relatively short and the drainage from its inner wall surfaces onto the bottom is not great. It will be appreciated that to a substantial extent the fiber of which the container is fabricated will absorb coating materials such as paraffin and the greatest absorption occurs at the point where the container is thickest, i. e., at its bottom. Hence if there is not a substantial amount of drainage or downflow of liquid coating substance from the inner faces of the side walls onto the bottom, the bottom may be inadequately coated and hence the container insufficiently prepared for the reception of a liquid. With a taller container it is found that there is usually an ample amount of downflow or drainage of coating material onto the bottom and hence it is generally found unnecessary to supply an auxiliary amount of coating material. The container R shown in Figure 5a, however, is relatively short, being in fact a container having a capacity of one half pint of liquid. The downflow of coating material onto the three ply bottom is relatively slight and it is necessary to provide means for supplementing the amount of coating material which would naturally gather upon the upper surface of the bottom as the result of the operations previously described.

This supplemental means includes a nozzle device 41 projecting through the top 35 of the housing for the rocking member 18, the discharge nozzle 42 of which is aligned with the vertical axis of the container R when the container is in its lowermost position. The rocking member 18 is provided with an aperture 18' axially aligned with the discharge nozzle 42 when member 18 is in its lowermost or vertical position so that when a supplemental body of coating material, as indicated at 43 in Figure 5a, is discharged from the nozzle 42 it will pass through aperture 18' and fall to the bottom of the container R.

The nozzle device 41 is of the pressure operated type provided with a valve which opens automatically when the pressure of the liquid within the device exceeds a predetermined amount and which closes automatically and sharply when the pressure falls below such amount, there being no dropping or discharge of coating material at any other time. Such pressure operated discharge devices are well-known and any suitable type of such device may be employed, the details thereof forming no part of the present invention. The means for supplying the coating material to the nozzle device 41, in synchronism with the movements of the conveyor handling member 18, will be hereinafter described and it is only necessary to state at this time that the device 41 receives fluid through the duct or conduit 72. The amount of material which may be discharged by the device may also be closely regulated. Each successive container by the time it reaches the position indicated at R in Figure 6 has received the necessary amount of coating material and is ready for movement toward the cooling unit. Prior to describing the means for chilling and hardening the coating, however, the means for maintaining the necessary supply of paraffin or other coating composition in the kettle or receptacle will be described.

In Figures 17, 18 and 19 a heated chamber for receiving solid blocks of coating material and converting these blocks into liquid form is illustrated. This comprises a box-like structure 45 affixed to the frame of the machine at an elevation higher than that of the receptacle 11. A door 46 at its outer end may be opened for the insertion thereinto of blocks of the solid coating material, two of which are illustrated in chain lines at 47 in Figure 18. The solid coating material thus inserted rests directly upon the uppermost of two parallel horizontally disposed metallic plates 48 which plates, together with continuous marginal spacing member 49 welded thereto define a chamber 50 into which live steam may be introduced by means of an inlet conduit 51 and from which the exhaust steam and water of condensation may be removed through conduit 52. Welded into aligned circular apertures formed in plates 48 are short tubes 53 and through these tubes 53 molten coating material may pass through the plates into the space below. A certain amount of the molten coating material may flow over the edges of the upper plate.

Just below this heating device is disposed a screening means comprising three parallel screens indicated at 54, 55 and 56, the uppermost screen 54 being of relatively coarse mesh and spaced above the remaining screens by spacers 57, the upper screen being removable. The intermediate screen 55 is of relatively fine mesh and is preferably welded at numerous points to the lowermost coarse mesh screen 56, screen 56 being in turn supported in a frame 58. The screening means thus described is supported above the upper surface of the bottom of the chest 45 by members 59 and the bottom of the chest slopes downwardly and inwardly toward the frame of the machine, as shown clearly in Figure 17. An outlet pipe or duct 45' leads from the lowest point of the chest 45 to a point above the body of coating material in the chamber 11, and molten paraffin or other coating material will make its escape from the chest 45 into container 11 after having passed through the screening device, any particles of foreign matter or impurities being intercepted by the screen.

During the operation of the coating apparatus the paraffin is removed from the tank or receptacle 11 by the containers at a relatively uniform rate and by the timely placing of fresh blocks of the material in the chamber 45 the level of the paraffin in container 11 may be maintained substantially constant. It will be observed from Figures 18 and 19 that each of the steam conduits 51 and 52 is provided, immediately adjacent the steam chamber within chest 45, with a collar or flange, pipe 51 having a flange 51' and pipe 52 a flange 52'. These flanges intercept any liquid coating material which might otherwise tend to pass along pipes 51 and 52 respectively and to escape from the chest 45 through the apertures formed therein for the reception of these pipes, and to cause such material to drip downwardly onto the screening device below.

Indicator means is provided for enabling the operator of the apparatus to ascertain the actual level of the paraffin within the container 11 at any time. This indicator is shown in Figure 15 and comprises two members, a scale 60 inscribed upon the upper end of the tube 61 and a pointer which comprises the upper end of a rod 62, rod 62 extending axially of the tube 61 and having secured to its lower end a float 63. Float 63 is enclosed within a cylindrical receptacle or sump

64, the interior of which is in constant communication with the interior of the receptacle 11 so that the level of the paraffin or other coating material within the sump stands at the same elevation as the level of the paraffin within the container 11. The level of the paraffin in the sump is indicated by the dotted line 65 and it will be readily perceived that, if this level should fall due to withdrawal of paraffin from container 11, the float 63 will fall and that the falling level will be indicated by lower positions of the upper end of rod 62 along the scale 60. The body of paraffin in the sump will always be quiescent so that the float will always indicate its true level.

The coating material within sump 64 is maintained at all times in molten and fluid condition by means of a heated coil 66 adapted to receive steam from a conduit 67 at its upper end, the lower end of coil 66 being in communication with an offtake conduit for exhaust steam and water of condensation, indicated at 68. A drainage pipe is indicated at 69 which pipe is normally closed by a valve and it is through this pipe that the paraffin contents of the sump and receptacle 11 may be withdrawn if desired, the lower end of the sump being at a lower elevation than the bottom of receptacle 11. Any collected water of condensation may also be removed through drain pipe 69.

A plunger pump is indicated at 70, this pump being mounted upon the side of the sump 64 and comprising a casing having a vertically disposed pump chamber the lower end of which communicates, by means of a port 71, with the interior of sump 64 below the level of the liquid within the sump, and also having an outlet port communicating with an offtake duct or conduit 72 which leads upwardly to the pressure operated nozzle device 41. The vertical pump chamber is provided with valves and a plunger 74 is vertically reciprocable therein, downward movement of this plunger closing the inlet valve of the pump and placing the liquid therein under pressure and upward movement of the plunger allowing the inlet valve to open and a fresh supply of coating liquid to be drawn into the pump chamber from the sump 64 while at the same time forcing a measured quantity of coating material upwardly to the nozzle device 41. The plunger 74 is retracted by means of a spring 75 encircling the plunger actuating rod and movement of the plunger upon its operating stroke is effected by means of a solenoid device generally indicated at 76. When energized the solenoid will effect downward movement of the plunger and force a measured quantity of coating material into pipe 72 by which it is delivered to the pressure operated nozzle device 41. When this pressure is initiated the automatically closing valve of the nozzle device 41 is opened and coating liquid is discharged therefrom, the flow of liquid from the pump and through discharge conduit 72 ceasing when the downward movement of the plunger 74 is terminated and the flow of liquid from nozzle 42 being simultaneously interrupted. In order that there may be no tendency for the liquid within the pump to harden this pump is maintained in heated condition while the apparatus is in operation, the pump casing having a vertical duct 77 formed therein and paralleling the pump chamber, steam being conducted to the upper end of this duct through a conduit 78 and exhaust steam and water of condensation being led away from the bottom of the duct through the conduit 79.

As will be perceived more readily from an in-

spection of Figure 5, the coating material duct 72 and the duct 78 for incoming steam are disposed in contiguous relationship from the vicinity of the pump chamber to a point just above the pressure operated nozzle device 41. In this way liquid coating material passing upwardly through duct 72 is maintained hot and freely flowing so long as the apparatus is in operation.

Certain other elements of the apparatus are 10 maintained in heated condition for various reasons, one being a heated trackway 82 for the freshly coated containers, illustrated most clearly in Figures 9, 10 and 11 and also indicated in the diagrammatic Figure 20. A second element 15 which is heated and which has not been previously described is the drip pan 83 shown in Figures 7 and 20, which underlies the trackway 82 and catches any paraffin which may drip downwardly from such trackway and leads it to 20 a point above the receptacle 11, into which it is discharged. A third element not previously described, and a portion of which is maintained in heated condition is the transverse supporting bracket 86, shown most clearly in Figures 6 and 7, the central portion of which is hollowed out to 25 provide a steam chamber 87 and is thereby maintained at a temperature above that at which the coating material will melt so that any drip from the containers passing across this bridging element will be maintained in liquid condition until it falls onto the heated drip pan 83 by which it is led back to the receptacle 11.

In Figure 20 all of the elements which are 30 maintained in heated condition are diagrammatically illustrated and the various conduits for leading steam to these elements and conduits for conducting away exhaust steam and water of condensation are also shown. It will be observed 35 that there is but a single steam line 89 for leading steam from a suitable source of supply, at the desired temperature, to the system of branch lines or conduits, and a single offtake 90 for water of condensation and exhaust steam. The various branch lines have previously been referred to for the most part and it need only be 40 further stated that the offtake line 22 leading from the heating chamber 20 within the coating applying unit 10 has a branch 22' leading to the chamber 87 and a further branch 22² which leads to the container trackway 82, conduit 22 continuing to the drip pan 83, to the lower end of which is connected the steam and condensate return line 92. The condensate return line from the heated trackway 82 is indicated at 93 and that from chamber 87 is indicated at 93'. It will also 45 be observed that the flow of steam to the steam chamber 25 beneath the container 11 is controlled by means of a thermostatically actuated valve which valve is diagrammatically illustrated at 94 in Figure 20, the movements of the valve being governed by the action of a thermostat 95 which projects into the receptacle 11 beneath the surface of the molten body of coating material therein. Should the temperature of the molten material fall the valve device 94 will be actuated 50 and the valve opened to permit increased volumes of steam to flow into the heating chamber 25 and should the temperature of the coating material become too high the thermostat will act to reduce the valve opening and decrease the flow of steam. The thermostatic means and the valve operatively connected thereto and controlled thereby may be of conventional type.

As has been previously mentioned, a container 55 which has progressed to the position in which it

is illustrated in chain lines in Figure 6, i. e., position R, has been completely coated and is ready for the next operation. Actuation of the pusher 31 through a single cycle of its movement causes the container R to move to the position R', the bottom of the container resting upon the spaced parallel rails 100 and 101 of the heated trackway, these rails having peaks 100' and 101', or relatively sharp ridges, upon which the container bottoms actually rest. The track rails are 10 hollow and steam introduced at 22² will flow, in the direction of the arrows, forwardly through the channel 102 in the rail 100 to the cross duct 103 and thence rearwardly through the conduit or channel 104 to the offtake line 93. Steam 15 thus circulating through the rails of the trackway maintains these rails in highly heated condition and imparts heat to the bottoms of the containers although, by reason of the practically knife edge contact between the container bottoms and the peaks 100' and 101', the amount of heat thus imparted will not be substantial.

It will be observed that the parallel rails of the trackway are interconnected at a number of points by cross members 105 the upper surfaces 20 of which are rounded and elevated somewhat above the plane of the peaks 100' and 101'. The container bottom engaging portions of the rails are also upwardly sloped immediately adjacent the cross members 105 so that a container moving from right to left (Figures 9 and 10) along the heated trackway will move upwardly along these several inclines, which are indicated at 100a, as the several cross members 105 are approached in succession, the bottom of the container making full sliding contact with each of the cross members 105 over which it passes. Sliding contact with these cross members, which are of course heated, results in the removal by wiping of excess coating material from the bottoms of the containers so that, as each container reaches the terminal end of the trackway after having passed several of the wiping devices, the coating material upon its undersurface will be smooth and continuous. The cross members 105 likewise 25 constitute devices for effecting rocking of the containers longitudinally of the trackway and facilitating distribution of the liquid coating material within the container over its bottom surface. Thus a container approaching a cross member 105 is tilted rearwardly and, after its center of gravity has passed over the cross member, will tilt forwardly, thus causing the coating material in liquid form resting upon its bottom to flow rearwardly and then forwardly, this action 30 being repeated at each cross member so that, in the case of a trackway having four cross members such as shown in Figures 9 and 10, each container passing thereon will be rocked first rearwardly and then forwardly four times. The liquid coating material upon the bottom of the container may likewise be flowed laterally if desired by the simple expedient of distorting the trackway so that the upper edges of the rails are at different elevations at various points along the length of the trackway. The trackway is fabricated of resilient metal and by means of the devices which are employed for the attachment of the same to the frame of the machine the desired distortion may be effected. Flowing of the liquid coating material back and forth over the container bottom causes all portions of the surface of the bottom to be washed with the liquid and insures that there are no uncoated 35 areas.

The means for advancing each container along the trackway, from station R' to station R² and then successively to stations R³, R⁴, etc. comprises a chain conveyor the details of which it is unnecessary to describe but which is shown in plan in Figure 6. The two chains 107 and 108 of the conveyor are endless and disposed in a common horizontal plane with the adjacent reaches of the chains in parallelism and guided upon suitable rails or trackways. Container engaging lugs or elements are indicated at 109 and, as the conveyor is operated, cooperating pairs of lugs are brought into simultaneous engagement with the rear wall of a container occupying the position R' in Figure 6, elements 109 maintaining contact with the container thus engaged, and advancing the container with a continuous motion until the container has been passed over the heated trackway and completely through the cooling unit of the apparatus. Any suitable type of conveyor means may, however, be employed for effecting the desired movements of the containers. The means for reciprocating the pusher 31 in synchronism with the movements of the conveyor likewise forms no portion of the present invention and any suitable means for effecting such movements may be employed.

The end of the heated trackway 82 projects into the cooling unit of the apparatus, as may be clearly seen in Figure 3. The cooling unit comprises the insulated box or housing 110 shown in longitudinal section in Figure 12 and in transverse sections in Figures 13 and 14, the top portion 111 of which is attached by hinges 112 (Figure 2) to the main or lower portion 113, apertures 114 and 115 in the ends of the housing being provided for the introduction and discharge of containers therefrom, and the several instrumentalities for the cooling or chilling of the coated containers are enclosed within this casing or housing. The conveyor chains 107 and 108 previously referred to extend through housing 110 and serve to continue the movement of the series of containers through this housing and out of the container discharge port 115 although, for the sake of clarity, these conveyor chains are not shown with the exception of the container engaging lugs 109 which are indicated in Figure 12.

As has been previously mentioned the forward end of the heated conveyor trackway projects through the aperture 114 and into the housing 110 for a short distance. Beneath this portion of the trackway is a drip pan 116 for collecting any paraffin or other coating substance which may fall from the containers while still on the heated trackway, this drip pan sloping downwardly and discharging into the drip pan 83 previously mentioned. In Figure 12 of the drawings the containers indicated at R⁵, R⁶ and R⁷ are resting upon the heated trackway while the remainder of the containers shown, i. e., container R⁸ and those lying to the left of this container (Figure 12) have passed from this trackway and have their closed lower ends immersed in the body of cooling liquid indicated at 118 which liquid, preferably water, rests in a longitudinally extending pan 119. Pan 119 is relatively long and narrow, is shallow, and has upwardly and inwardly turned flanges 119'. The liquid is cooled to a low temperature artificially and is of relatively high heat conductivity so that the temperature of each container bottom, which is of multi-ply construction, and also heavily coated with coating material, is rapidly reduced. The liquid body 118 is

of such length that by the time that container R⁵ reaches the position R⁹ both the multi-ply paper bottom and the paraffin coatings above and below the same have been thoroughly chilled and the coating material rendered quite hard. The container R⁹ has been in fact lifted out of the water or liquid body, having moved up inclined guides 120 so as to pass over the header 121 which forms one end of the liquid pan. A similar header 122 comprises the other end of this pan and these headers likewise constitute the pan supports, being themselves supported upon brackets or rests 123 and 124 rigidly supported within the housing 110. Further advance of container R⁹ will cause it to move through aperture 115 from where it may pass to other instrumentalities for charging and closing the same. It will be observed that header 121 has formed therein a longitudinally extending aperture 125 and that header 122 has a similar longitudinally extending aperture 126. These respective bores or apertures are in communication with the ends of a plurality of pipes or tubes 127 extending longitudinally of pan 119 and positioned approximately at the bottom of the pan. Cooling liquid is passed through the relatively small tubes 127 from one header to the other, by means to be hereinafter more particularly described, and the body of liquid in the pan thereby maintained at a low temperature preferably, when the liquid is water, just above the freezing point.

During the time that each container is moved from position R⁵ to position R⁹ that portion thereof which lies above the level of the liquid in pan 119 is subjected to the action of a cooling gas, preferably air cooled to a low temperature, all of the exterior wall surfaces and also the interior wall surfaces being acted upon by the cooled gaseous streams, the effect of which is to chill and harden the coating material upon the upper portions of each container so that, when the container reaches the position indicated at R⁹, the coating material covering its entire upper portion, as well as the coating material on its bottom, has been thoroughly chilled and hardened.

A blower or fan is indicated at 130, this fan being mounted upon the bottom of the housing and the rotor of the fan being connected by means of a shaft 131 with a power source such as the electric motor 132 which is positioned without the housing and supported upon a bracket 133. The blower 130 is of the type which receives or draws in air axially of the rotor from both ends, arrows 134 indicating the directions of air inflow into the ends of the blower. The air thus drawn in is discharged transversely of the blower axis and the arrows 135, Figures 13 and 14, indicate the direction of flow of air discharged by the blower. A vertically extending baffle is indicated at 136 and the current of air discharged by the blower is directed upwardly between baffle 136 and the adjacent wall of the housing 110, passes over a plurality of horizontally extending ducts 137 equipped with heat collecting fins 138 and thence upwardly toward the top of the housing, as indicated by the arrows in Figures 13 and 14. A cooling fluid, which may be either a liquid or a gas, is circulated through tubes 137 by means hereinafter to be described and the air passing past these tubes is cooled by contact therewith and with the heat collecting fins 138. Toward the top of the housing the stream of air meets a plurality of inclined baffling plates 139, 140 and 141, rigidly supported in position, which serve to

direct the air upwardly and inwardly toward the series of containers so that the adjacent longitudinally extending side surfaces of these containers are directly subjected to impinging air streams and the transversely extending forward and rear side walls of the container are likewise subjected to the action of such streams. A certain amount of the upflowing air stream will pass over the lower or leading edge of the baffle plate 141 and along the lower surface of the top of the housing where it will meet and be deflected downwardly by the curved baffle 142 into the interiors of the several containers, thus causing rapid circulation of air within these interiors and 15 direct cooling of the inner coating of coating material. A substantial stream of cooled air will continue past the deflector 142 and will be turned downwardly by the downwardly inclined lower surface of the housing top after which this current will be deflected downwardly and inwardly 20 toward the containers by the series of baffles 143, 144 and 145, thereby being directed against those sides of the containers not previously directly contacted by rapidly flowing air streams. Finally 25 the air is drawn downwardly through a second series of tubes 137 which lie to the left of the baffle 136 (Figure 14) and provided with heat collecting fins 138, these tubes likewise containing a circulating cooling fluid, either gas or liquid, 30 and again passes to the fan or blower for recirculation. By the means described, therefore, a body of cooling gas may be continuously circulated within the housing and caused by baffling devices to flow past all exposed surfaces of the series of 35 containers therein.

While the housing is not gas-tight, having the open apertures 114 and 115 in its ends, there will be but little cooled air escape in the ordinary operation of the unit and naturally any air escaping will be replenished automatically. In Figure 40 14 a small tube is indicated at 146, the discharge end of which overlies the liquid pan 119. It is through this tube that a regulated flow of liquid is passed into the liquid pan to replace that 45 which is carried from the unit upon the bottoms of the containers passing therethrough. The flow of liquid may be regulated by a needle valve and any excess liquid supplied will pass over the header 121 and fall onto a drip pan 147, by which 50 it is conducted to a point of discharge.

The means for circulating a cooling fluid through the conduits previously described is diagrammatically illustrated in Figure 21. In this figure a supply main is indicated at 150, this main 55 leading from any suitable source of cooling fluid. While the cooling fluid may be either in gaseous or liquid form, the apparatus which has been illustrated is one which has been primarily designed for use with brine as a cooling medium, brine being introduced into the system from a suitable source through the supply main 150 at a temperature which may vary between zero degrees and 20° F. From main 150 a branch line 151 leads to the system or battery of air cooling 60 tubes 137 and from this series of tubes the brine passes into tubular casing 152, thence into conduit 153 and finally to discharge main 154 by which it is conducted to a brine cooling and recirculating mechanism which is not illustrated. A 65 second branch line leading from main 150 is indicated at 155, this branch leading to header 122 which header, as has been previously explained, communicates with a second header 121 by means of a plurality of tubes 127, one only of which is 70 shown in Figure 21. From header 121 the brine 75

is conducted through conduit 156 to a cylindrical housing 157 and is thence conducted through conduit 158 to the brine return main 154.

The housings 152 and 157 previously referred to contain thermostatic elements 159 and 160 respectively, indicated in dotted lines, which elements are preferably of the fluid expansion type and either mechanically or by fluid pressure means operatively connect two control valves 161 and 162 respectively, valve 161 controlling the flow of cooling liquid through branch 151 to the air cooling tubes 137 and valve 162 controlling the flow of brine through conduit 155 to the liquid cooling tubes 127. It will be observed that the thermostatic elements 159 and 160 are both so disposed in the fluid circulating system that each is encircled by a body of brine which has already performed its cooling functions and hence it is clear that valves 161 and 162 are controlled in accordance with variations in the temperatures of the outflowing brine streams. The system is entirely automatic in operation and valves 161 and 162 are of course independently regulated so that the body of water in pan 119 may be subjected to the action of additional or reduced amounts of cooling brine, without requiring the circulation of additional or reduced amounts of cooling brine through the air cooling coils 137 or vice versa. It will be understood that no novelty is claimed for the details of construction of the thermostat means for controlling the operation of the valves 161 and 162 respectively and that any suitable thermostatic devices available may be employed. Preferably, however, thermostats are of the gas expansion type and the variations in gas pressure within thermostatic elements 159 and 162 cause the operation of bellows devices within the housings diagrammatically illustrated at 163 and 164 respectively, which bellows devices are directly connected to the valves through valve stems 165 and 166.

It is thus seen that a cooling unit has been provided, within which freshly coated containers are subjected to the action of cooling media having different heat conducting properties so that, notwithstanding the fact that certain portions of the containers are more difficult to cool than others, all portions thereof are brought to completely cooled condition practically simultaneously. It is apparent that the method of cooling disclosed may be practiced in structures which differ widely from that which has been disclosed by way of example. Furthermore any suitable gas may be employed rather than air and the actual cooling of the air and liquid may be effected by an artificial cooling mechanism of the gas expansion type, rather than of the brine circulation type.

The heated trackway 100 also embodies three cross connecting webs 100² each provided with a central slot 100³ (see Figure 25) and lateral apertures 100⁴. A securing screw 100⁵ passes downwardly through each slot and set screws 100⁶ pass through the apertures 100⁴, the securing screw entering a threaded recess in a supporting member S the ends of which are attached to rails S' by brackets S², one of which is shown in Figure 7. By manipulating the set screws and securing screws the trackway may be raised or lowered as desired and also tilted or distorted to obtain the desired inclination of a container passing over the same and hence the desired distribution of coating material over its bottom.

Having thus described the invention, what is claimed as new and desired to be secured by Letters Patent is:

1. Mechanism of the class described comprising, in combination, a container handling device for placing bottom end lowermost upon a conveyor, an open topped tubular paper container the bottom of which is closed and the inner wall surfaces of which are coated with coating material in molten condition, mechanism spaced from said device for chilling and solidifying such molten coating, and a conveyor for receiving such an interiorly coated container deposited thereon at one point by said device and transmitting the same to said chilling mechanism, said conveyor including means for heating the container bottom to maintain the molten material collected thereon in molten condition and means to rock the container as it advances so that such molten material will be caused to flow over all areas of the container bottom.

2. Mechanism of the class described comprising, in combination, a container handling device for placing bottom end lowermost upon a conveyor, an open topped tubular paper container the bottom of which is closed and the inner wall surfaces of which are coated with coating material in molten condition, mechanism spaced from said device for chilling and solidifying such molten coating, and a conveyor for receiving such an interiorly coated container deposited thereon at one point by said devices and transmitting the same to said chilling mechanism, said conveyor including a trackway upon which the containers rest and along which they are moved, and means for heating the trackway, said trackway having uneven container engaging surfaces to cause the container to rock as it advances so that molten material collected on the container bottom will be maintained in liquid condition and caused to flow over all areas of the container bottom before solidifying.

3. Mechanism of the class described comprising, in combination, a container handling device for placing bottom end lowermost upon a conveyor, an open topped tubular paper container the bottom of which is closed and the inner wall surfaces of which are coated with coating material in molten condition, mechanism spaced from said device for chilling and solidifying such molten coating, and a conveyor for receiving such an interiorly coated container deposited thereon at one point by said device and transmitting the same to said chilling mechanism, said conveyor including a trackway upon which the containers rest and along which they are moved, and means for heating the trackway, said trackway having a plurality of spaced transversely extending raised portions over which the containers move and which cause the containers to rock forwardly and rearwardly as they advance.

4. Mechanism of the class described comprising, in combination, a container handling device for placing bottom end lowermost upon a conveyor, an open topped tubular paper container the bottom of which is closed and the inner wall surfaces of which are coated with coating material in molten condition, mechanism spaced from said device for chilling and solidifying such molten coating, and a conveyor for receiving such an interiorly coated container deposited thereon at one point by said device and transmitting the same to said chilling mechanism, said conveyor including a trackway upon which the containers

rest and along which they are moved, said trackway being distortable to provide container supporting surfaces at different levels as desired, to effect tilting of a container being moved over the same, and means for maintaining the trackway in any desired condition of distortion.

5. Mechanism of the class described comprising, in combination, a container handling device for placing bottom end lowermost upon a conveyor, an open topped tubular paper container the bottom of which is closed and the inner wall surfaces of which are coated with coating material in molten condition, mechanism spaced from said device for chilling and solidifying such molten coating, and a conveyor for receiving such an interiorly coated container deposited thereon at one point by said device and transmitting the same to said chilling mechanism, said conveyor including a horizontally disposed elongated one-piece trackway for slidably supporting the container bottoms, said trackway being formed with passages for a fluid heating medium and with container supporting surfaces disposed at different levels to cause the containers to rock as they slide, whereby any liquid coating substance resting upon the container bottom will be maintained in flowable condition and caused to flow over all areas of the bottom as the container is advanced toward the chilling means.

6. Mechanism of the class described comprising, in combination, means for applying to the interior wall surfaces of a tubular paper container, the bottom of which is closed, a coating of a molten coating material and thereafter inverting the container to drain the same, means for thereafter disposing the interiorly coated container in a predetermined position with open

end uppermost, and means for promptly introducing into the container after it is so drained and positioned a measured quantity of molten coating material to supplement the coating previously applied and form a thicker coating over the surface of the bottom.

7. The combination set forth in claim 6 in which heating means is provided for maintaining the coated container warm, and the coating 10 therein in fluid condition, until after the introduction of such additional molten coating material.

8. Mechanism for interiorly coating a paper container one end of which is open and the other end closed, said mechanism including a receptacle for a bath of molten coating material, means for successively passing containers through said bath to coat all surfaces thereof and for thereafter draining the same, an intermittently operable pump for removing measured amounts of coating material from the receptacle and discharging the same under pressure, a fluid discharge nozzle, a conduit connecting the pump and nozzle, and means for positioning the open 20 end of a previously coated container in the line of discharge of coating material from said nozzle to receive within the same a small additional amount of coating material when the nozzle is actuated, and means for thereafter further advancing the container.

9. The combination set forth in claim 8 in which means is provided for heating the pump, nozzle and conduit connecting the same, for the purpose set forth.

IRVING SNADER.
JAMES F. EARP, JR.
